GARMENT WITH HOOD AND POCKET
THEREFOR

Jack Werber, Newburgh, N. Y.

Application August 7, 1952, Serial No. 303,025

4 Claims. (Cl. 2-84)

1

This invention is an improved outer garment, especially a garment for protecting not only the body, but also the head when needed.

An important object of my invention is to provide a coat or similar article of clothing with a hood attached to the back just below the collar, the garment having an inside space or pocket into which the hood can be stowed in readiness to be pulled out when the wearer desires. The hood is united to the garment along the lower edge of an opening leading to the pocket, and the upper edge of said opening and both the inner and outer faces of the cloth of the hood adjacent said lower edge have fastening devices by which the pocket can be closed, when the hood is in or out. When the hood is not in use on the head, the garment has all the appearance of a coat or the like without a hood.

Other objects are made clear in the following description and a practical embodiment of the invention is illustrated in the drawings. The novel features are pointed out in the claims, but I do not wish to be limited to the exact construction shown herein. The design may of course be varied in minor respects without omitting or deviating from any of the essential characteristics.

On the drawings:

Figure 1 is a vertical section of a coat, cloak, etc., according to my invention, taken through the back and showing diagrammatically the arrangement of the layers of cloth with the collar at the top and the hood inside the back.

Figure 2 is a rear elevation of the garment as it looks when spread out, showing the hood stowed away in the pocket below the collar and the pocket closed.

Figure 3 is a similar rear elevation showing the hood pulled out and ready to be raised to cover the owner's head.

Figure 4 is a section similar to Figure 1 showing the arrangement of parts with the hood pulled out.

Figure 5 is a rear elevation of the upper part of the garment, spread out showing the hood pulled out of the pocket, and the pocket not yet closed; and

Figure 6 is a perspective view of the garment with the hood out and raised to the position in which it covers all the head, except the face.

The garment is made of an outer layer 1, and an inside lining 2. It has sleeves 3 and pockets 4 and suitable fastening means to hold it closed in front. The neck opening at the top has a collar 5.

2

Across the back just below the junction of the collar with the body of the coat is a horizontal slit or opening 6. The hood 7 shaped to envelop the top and sides of the head, is made fast along its lower edge to the cloth 1 at the lower edge of the slit, and the space between the outer layer 1 and lining 2 constitutes a pocket into which the hood 7 can be stowed. The space is large enough to allow the hood to be spread out and disposed in a flattened state, so that the back will be smooth and the garment can then be worn with neatness and comfort.

Along the upper edge of the slot 6 is a length of tape 8, one edge of which is stitched to the cloth 1, and having a row of fastening devices 9 along its free lower or opposite edge. The ends of the tape 8 are at the ends of the slit 6. The row of fastener devices carries a slide fastener member 10, which can be slipped along the fasteners 9 but cannot be detached; because the fasteners 9 have a flattened head 11 at one end and a stop 12 at the other. The member 10 moves from the head 11 towards the stop 12 to actuate the fastener devices 9, to close the opening.

As indicated in Figure 4, the lower edge of the hood when the hood is pulled out and upward is upon the outer face of the cloth 1 along the lower edge of the slot 6. Figure 1 shows the arrangement when the hood is in between the layer 1 and lining 2. In such position of the layer and hood, a length of tape 13 is under the cloth 1, that is against its inner face along the lower edge of the slot 6; and upon the inner face of the hood along the lower edge of the opening 6 is another length of tape 14. These strips overlap each other along one edge, with the edges of the hood 7 and the layer 1 along the lower edge of the slit 6 between them. The tapes 13 and 14 and the hood 7 and layer 1 at the back of the garment are carefully stitched together, joining the hood to the garment and securing the strips 13 and 14 to both faces of the hood at its junction with the layer 1. Along the opposite edges, the strips of tape 13 and 14 have rows of fastener devices 15, and 16 respectively, similar to the devices 9, the ends of the rows 15 and 16 being flush with the ends of the row 9 along the upper edge of the slit 6. As further shown in Figure 1, when the hood is inside of the garment, the strip 13 bears its fastener elements 15 along the edge that is lowermost, while the elements 16 lie along the edge of the tape 14 that is uppermost. At one end, the rows 15 and 16 respectively have stops 17 and 18 adjacent the stop 12, and the opposite ends of the rows 15 and 16 have guide studs

19 and 20 respectively, adjacent the head 11. The ends of these tapes 13 and 14, bearing the studs 19 and 20, have unattached portions to facilitate manipulation of the guide studs 19 and 20.

The head 11 is affixed along one of its sides to the row of fastener devices 9, and projects at its opposite side, and there has an opening in one end there to receive either stud 19 or 20. When the hood is pushed through the slit 6 into the pocket or space between the layer 1 and lining 2 the stud 20 of the fastener devices 16 on the tape 14 is pushed through the member 10 and into the head 11. The member 10 can then be actuated to connect the fasteners 16 on the tape 14 to the fasteners 9 and fully close the pocket to cover and conceal the hood.

When the hood is to be taken out of the pocket and pulled over the wearer's head, the member 10 is moved to disengage the fastener device 16 on the tape 14 from the fasteners 9. The slit 6 is thus opened. When the hood is extracted and arranged to cover the head, it screens the slit 6 and the slit can now be closed by inserting the stud 19 on the tape 13 into the member 10 and the head 11. The member is now moved to cause the fastener devices 9 to engage and hold the fastener devices 15 on the outer tape 13. The member 10 has the usual tab 21 to be seized by the fingers when the member is to be operated.

When the hood is inside the coat the collar can be turned down to cover the tape 14 with its fastener devices 16 and the fastener devices 9. When the hood is out, the collar can be turned up to cover the tapes 8 and 13 and the fastener devices 9 and 15, so that these devices do not touch the wearer's neck.

When the hood is inside the tape 14 will be connected to the tape 8, and will be above the tape 13, which is then turned inward and downward. When the hood is out and lifted, the tape 13 will be joined to the tape 8 by the elements 15 and 9 and will be above the tape 14, which will be folded down outside against the back of the garment.

As illustrated particularly on Figure 1, the layer 1 has its upper edge 23 turned over inward and the tape 13 has its plain edge inserted under this folded-over edge of the layer 1. The opposite or lower edge of this tape, in the position of the parts on Figure 1 is the edge that has the fastener elements 15. The hood now inside the garment, extends downward, and it is laid against the edge 23. The other tape 14 is secured against the hood, with its elements 16 along the upper edge. A line of stitches 24 joins the folded edge 23 to the tape 14, and another line of stitches 25 unites the tape 14, hood 7 and edge 23. Two more lines of stitches 26 below the fold 23 pass through the tape 14, edge of the hood 7, tape 13 and layer 1 together. The tapes are thus securely attached to the layer 1 and the hood 7.

The collar may have two layers of curved strips 22 connecting it to the lining 2 and tape 8.

Having described my invention, what I believe to be new is:

1. A garment having a body with a neck opening and a collar at said opening, the body comprising an outer layer and an inner lining at the back below the collar, the outer layer having an elongated transversely extending opening below the collar, a hood joined to said layer along the lower edge of said opening, to be stowed between the layer and the lining or pulled out to cover the wearer's head, a row of fastening devices on said layer along the upper edge

of the opening and a transverse row of other fastening devices secured to one face of the hood adjacent its junction with said layer, to be engaged with the first-named devices, and close said opening when the hood is inside the garment, additional fastening devices in a transverse row on the other face of the hood adjacent said junction to engage the first-named devices and close the opening when the hood is pulled out of said garment, said hood being large enough so that when in position on the wearer's head, the collar is within the hood and lies over and covers said first-named row and said additional fastening devices, the other row of fastening devices remaining exposed on the outer side of the hood, and a single fastener member slidably attached to the first-named row for alternately connecting said first-named row to either of the other two rows.

2. A garment having a body with a neck opening and a collar at said opening, the body comprising an outer layer and an inner lining at the back below the collar, the outer layer having an elongated transversely extending opening below the collar, a hood joined to said layer along the lower edge of said opening, to be stowed between the layer and lining or pulled out to cover the wearer's head, a row of fastening devices on said layer along the upper edge of the opening and a transverse row of other fastening devices secured to one face of the hood adjacent its junction with said layer, to be engaged with the first-named devices, and close said opening when the hood is inside the garment, additional fastening devices in a transverse row on the other face of the hood adjacent said junction to engage the first-named devices and close the opening when the hood is pulled out of said garment, said hood being large enough so that when in position on the wearer's head, the collar is within the hood and lies over and covers said first-named row and said additional fastening devices, the other row of fastening devices remaining exposed on the outer side of the hood, and a sliding member on the first-named row at the edge of the opening to connect the first-named row with either of the other rows, the first-named row having a head at one end and each of the other rows having a stud adjacent said head to dispose either of said other rows to be connected to the first-named row by said member.

3. A garment having a body with a neck opening and a collar at said opening, the body comprising an outer layer and an inner lining at the back below the collar, the outer layer having an elongated transversely extending opening below the collar, a hood joined to said layer along the lower edge of said opening, to be stowed between the layer and lining or pulled out to cover the wearer's head, a row of fastening devices on said layer along the upper edge of the opening and a transverse row of other fastening devices secured to one face of the hood adjacent its junction with said layer, to be engaged with the first-named devices, and close said opening when the hood is inside the garment, additional fastening devices in a transverse row on the other face of the hood adjacent said junction to engage the first-named devices and close the opening when the hood is pulled out of said body, said hood being large enough so that when in position on the wearer's head, the collar is within the hood and lies over and covers said first-named row and said additional fastening devices, the other row of fastening devices remaining exposed

on the outer side of the hood, the hood when pulled out being against the outer face of the layer at the junction, a strip of tape secured over the outer face of the hood along said junction, another strip of tape secured to the other face of the hood along said junction, the additional and other fastening devices being disposed along the opposite edges of said tapes and a sliding member on the first row to connect the first-named row to either of the other rows, the first-named row having a head at one end and each of the other rows having a stud adjacent said head to dispose either of said other rows to be connected to the first-named row by said member.

4. A garment having a body with a neck opening and a collar at said opening, the body comprising an outer layer and an inner lining at the back below the collar, the outer layer having an elongated transversely extending opening below the collar, a hood joined to said layer along the lower edge of said opening, to be stowed between the layer and lining and pulled out to cover the wearer's head, a row of fastening devices on said layer along the upper edge of the opening and a transverse row of other fastening devices secured to one face of the hood adjacent its junction with said layer, to be engaged with the first-named devices, and close said opening when the hood is inside the garment, additional fas- 30

tening devices in a transverse row on the other face of the hood adjacent said junction to engage the first-named devices and close the opening when the hood is pulled out of said body, said hood being large enough so that when in position on the wearer's head, the collar is within the hood and lies over and covers said first-named row and said additional fastening devices, the other row of fastening devices remaining exposed on the outer side of the hood, the hood when pulled out being against the outer face of the layer along the junction, a strip of tape secured over the outer face of the hood along said junction, another strip of tape secured to the other face of the hood along said junction, the additional and other fastening devices being disposed along the opposite edges of said tapes and a sliding member on the first row to connect the first-named row to either of the other rows, said tapes having said junction between them, and the first-named tape encircling the outside of the hood at the lower part when the hood envelops the head of the wearer.
